RICHARD VOSE, OF NEW YORK, N. Y.

Letters Patent No. 71,926, dated December 10, 1867.

IMPROVED CAR-SPRING.

The Schedule referred to in these Letters Patent and making part of the same.

TO ALL WHOM IT MAY CONCERN:

Be it known that I, RICHARD VOSE, of the city, county, and State of New York, have invented a new and useful Improvement in Volute Springs for Railroad-Cars and other vehicles, and for other purposes; and I do hereby declare the following to be a full and exact description thereof, reference being had to the accompanying drawings, forming a part of this specification, in which—

Figure 1 is an elevation, and

Figure 2 a central longitudinal section of my improved spring, the section, fig. 2, illustrating a modification of the form of invention shown in fig. 1.

The nature of my invention consists in the use of a bar of metal, made thicker at one edge or side than the other, and tapering, either with a straight face, as illustrated in fig. 1, or with an inward curve, as shown in fig. 2, from the thick to the thinner edge. The decrease in the thickness of the bar, transversely from side to side, (that is to say in the line of its width,) may be disposed wholly upon one face, so as to approach in its cross-section the form substantially of a right-angled triangle, or on both, so as to present in such section substantially the form of an acute-angled triangle, although I do not contemplate reducing the thinner side of the bar in all cases to a very fine edge or angle. The bar may be rolled out in this form in its manufacture by passing the same through between tapering-rolls properly arranged.

In constructing my improved springs out of bars of metal so formed and shaped, I coil them spirally upon suitable mandrels, so that the thicker edge shall be uppermost in the spring, and temper them in the manner followed in the manufacture of the ordinary forms of volute springs. Although I find it best to place the thicker edge of the bar uppermost in the spring, yet I do not confine myself to this arrangement thereof.

In these my improved springs I obtain more surely greater uniformity of temper than in the form of springs now in use, from the fact that, when placed coiled in the tempering-bath, the tempering-oils come readily in contact with every part of the metal. I also obtain, from a reduced weight of metal in the spring, the same, or, in some forms, greater resilient power than is found in the ordinary forms of springs.

Having thus fully described my invention, I claim as new, and desire to secure by Letters Patent—

A volute spring, formed or constructed of a coiled metallic bar, whose thickness is greater transversely upon one edge thereof than at any other point therein, substantially as and for the purpose herein set forth.

The foregoing specification of my improved volute spring signed by me, this eleventh day of September, A. D. 1867.

RICH'D VOSE.
